UNITED STATES PATENT OFFICE.

CHAUNCEY F. ALLEN, OF WATERBURY, CONNECTICUT.

CORSET.

SPECIFICATION forming part of Letters Patent No. 230,163, dated July 20, 1880.

Application filed January 28, 1880.

To all whom it may concern:

Be it known that I, CHAUNCEY F. ALLEN, of Waterbury, county of New Haven, Connecticut, have invented an Improvement in Corsets, 5 of which the following is a specification.

My invention is a corset constructed, as fully described hereinafter, for the purpose of securing a proper fit and support the corset beneath the arms and at the waist without 10 duly restricting the movements of the body at such points.

In the drawings forming part of this specification, Figure 1 is a view showing one side of my corset; Fig. 2, a modification, the wing 15 being thrown back; Fig. 3, another modification.

A represents one side of a corset, which may be in one piece, as in Fig. 3, or in two or more pieces connected by lacings, as in Fig. 1. To 20 this side, above the line x of the waist, I apply one or more wings, B, stiffened by bones, cords, quilting, hair or grass fabric, or otherwise. Each wing is secured to the side A at one edge, y, being attached by sewing at the 25 seam of the corset, by eyeleting, lacing, or otherwise, in any suitable manner, and the opposite edge of the wing is provided with holes to receive a lace, b, by which the wing may be connected at this edge to hooks on the body 30 or to the edge of the opposite wing. Said wing or wings rest or bear with their lower edges upon the hip, and stiffen the corset between the hip and the shoulder without affecting the flexibility of the hip portion, and render the side rigid, while the movements of the 35 body are not interfered with. Thus each wing supports the corset between the points 1, 2, while that part of the corset beneath the wing is soft and pliable.

Another advantage is that by tightening 40 the lace b or loosening it the corset may be made to fit exactly to the body.

The application of the re-enforcing piece or pieces B permits the side of the corset to be stiffened by the use of cords c, which may be 45 arranged diagonally, as shown in Fig. 2, and which impart the proper rigidity and prevent the corset from creeping up without rendering the corset hard and abrading the body of the wearer. In some instances, where two wings 50 are used, they may extend to the lower edge, the lacing between them permitting sufficient flexibility over the hip.

In most instances great advantage will result from using a lacing of rubber or other 55 elastic material covered by braiding with cotton or silk. This secures the parts together, while preventing binding and strictures.

Without limiting myself to the precise construction and mode of attaching and tightening the wings shown,

I claim—

1. A corset provided with one or more wings, B, each attached externally to the body at one edge, overlapping the body, and extending beneath the arm from above the waist downward, and provided with lacing or other fastening a, substantially as set forth.

2. The combination of the wings and the sides corded beneath the wings, substantially 70 as set forth.

In testimony whereof I have signed my name to this specification in the presence of two subscribing witnesses.

CHAUNCEY F. ALLEN.
